UNITED STATES PATENT OFFICE.

LOGAN WILLARD MULFORD, OF NEW YORK, N. Y.

VAULT-LIGHT CONSTRUCTION AND METHOD OF SECURING LENSES THEREIN.

1,159,858.

Specification of Letters Patent.

Patented Nov. 9, 1915.

Application filed July 15, 1915. Serial No. 39,961.

To all whom it may concern:

Be it known that I, LOGAN WILLARD MULFORD, a citizen of the United States, residing in the city and county of New York, State 5 of New York, have invented a new and useful Vault-Light Construction and Method of Securing Lenses Therein, of which the following is a specification.

In the installation of vaultlight, floorlight, skylight and similar constructions, wherein a lens or tile is embedded in the concrete, considerable difficulty has heretofore arisen in replacing the broken lenses, the breaking or cracking of which occurs 10 due to traffic and climatic conditions. In the methods ordinarily employed in replacing broken lenses, it has been deemed necessary to employ a skilled workman to remove the broken lens and replace it with a 15 new one. It is also sometimes necessary to chip away a portion of the concrete surrounding the lens which is a slow and painstaking operation so that considerable expense has been involved in replacing the 20 lenses without detracting from the appearance and stability of the finished construction.

With the above in view, my present invention consists of a novel method of 25 interlocking the glass with the concrete, and a novel watertight cement lock joint resulting from the steps of my method.

It further consists of a novel vaultlight or similar construction, in which the original lens or glass is provided with an outwardly projecting annular rib, the outer contour of which is preferably convex so that when the concrete is placed around the lens, a concave annular groove will be 30 formed in the concrete. The replaceable lens is provided with an annular groove, the inner face of which is preferably concave, so that after the original lens has been 35 broken out, an annular groove will be formed in the concrete. The sides of the concrete are buttered with fresh cement which fills the groove in the old cement and the lens is buttered with soft cement 40 which fills the groove in the lens so that 45 when the parts are assembled, the two ribs of soft concrete form a homogeneous mass and a cement or concrete lock is provided 50 to retain the lens in assembled position.

Other novel features of construction and advantage will hereinafter more clearly appear in the detailed description. 55

For the purpose of illustrating my invention, I have shown in the accompanying drawings one form thereof which is at present preferred by me, since the same will 60 give in practice satisfactory and reliable results, although it is to be understood that the various instrumentalities of which my invention consists can be variously arranged and organized and that my invention is not 65 limited to the precise arrangement and organization of these instrumentalities as herein shown and described.

Figure 1 represents a sectional elevation of a vaultlight construction having the original lens or glass in position, one of the lenses being shown in side elevation. Fig. 2 represents a sectional elevation of a vaultlight construction, showing the same as it appears after the original lens has been 75 replaced and after a cement lock embodying my invention has been formed to interlock the lens and the concrete, one of the lenses being shown in side elevation. Fig. 3 represents a sectional view of a portion of the 80 construction ready to receive the lens. Fig. 4 represents a sectional view of the lens with the rib of cement in place.

Similar numerals of reference indicate corresponding parts in the figures. 85

Referring to the drawings: In my prior Patent, No. 1,021,548, granted to me on the 26th day of March, 1912, I have described and broadly claimed a novel vaultlight, skylight, and floorlight construction, where- 90 in a preformed slab of reinforced concrete is employed, adapted to receive the lenses, and provided with bonding elements which are first placed over the opening to be cov- 95 ered. The second layer of concrete inter- locks with the bonding elements and sur- 100 rounds the lenses to retain them in position. In the present instance, I have preferred to illustrate my present invention in conjunc- 105 tion with such type of construction, al- though as is apparent, it is not limited to such type of construction and may be em- ployed in connection with any desired type of reinforced or other concrete construction where lenses or tiles are to be employed.

1 designates a preformed slab having

metal reinforcements 2 of any desired type extending longitudinally therethrough and preferably formed of deformed rods.

3 designates metal reinforcements extending through the preformed slab at an angle to the reinforcements 2 and illustrated as consisting of beams, the upper ends of which extend above the preformed slab and form bonding elements which are embedded in the upper layer of cement or concrete 4, which, as seen in Fig. 1, also embeds the original lenses 5. The original lenses 5 are provided, intermediate their top and bottom, with an outwardly extending annular rib 6, the outer face 7 of which is preferably convex. The sides of the lenses preferably taper downwardly from the top, as indicated at 8, and this taper also continues beneath the annular rib 6, as indicated at 9. An annular flange 10 is provided at the bottom of the lenses, which form a shoulder 11, which rests on a shoulder 12 formed in the concrete. The bottom of the lens may be provided, if desired, with the recess 13. The upper portions of the sides of the lenses are coated with a malleable coating 14 in order to form a watertight joint at the upper portion of the lens. When an original lens, as seen in Fig. 1, becomes cracked or broken, such broken lens is knocked out of the reinforced construction, thereby leaving an annular groove 15, which in the form illustrated, has a concave formation.

Referring now to Fig. 2, 16 designates the replaceable lenses, which are preferably made slightly less in diameter than the original lenses 5 and are provided with the upper downwardly tapered side walls 17, which merge into the annular groove 18, which latter is preferably of a concave formation and located at the same relative position between the top and bottom of the lens, as is the annular rib 6 of the original lens. The side wall of the replaceable lens 16 is tapered downwardly from the bottom of the groove 18, as indicated at 19, and forms a shoulder 20 which rests on the shoulder 12 of the concrete. The bottom of the replaceable lens preferably terminates in an annular flange 21, which serves to center the lenses in a similar manner as does the bottom flange 10 of the original lens 5. After the original lens has been broken out, the sides of the concrete are buttered or coated with fresh cement or concrete which fills the groove 15 in the old concrete. The side walls of the lens are buttered with soft cement, which fills the groove 18 in the lens, so that when the lens is pressed into position, the two ribs of soft concrete become homogeneous and form an annular watertight cement lock 22 to secure the lens in place. The side wall of the lens or glass near its upper end is provided with a malleable coating 23 in order to render the con-

struction watertight at this point and to prevent leakage through such portion of the construction.

The preformed slab 1 is provided with the openings 24 beneath the lenses or glasses, the walls of such openings preferably diverging toward the bottom of the preformed slab. 70

It will now be apparent that in carrying out my novel method, I form the original lenses with outwardly projecting annular ribs and embed or surround them with concrete. These original lenses, when it is desired to replace them, are broken out. A new lens is formed with an annular groove. Such new lens is coated with fresh cement which fills the groove thereof and the wall of the opening is coated with fresh cement and the groove in the wall filled with fresh cement. The lenses are then assembled in their openings and the cement allowed to set, whereupon an annular watertight cement lock joint is formed between the new glass and the old concrete. In accordance with my present invention, new lenses can be replaced by the use of unskilled labor, with a minimum of expense, and without detracting from the appearance of the finished construction.

While in the present instance, I have preferred to show the annular grooves common to the concrete and replaceable lens as having a concave formation, it will be apparent that in the broad spirit and scope of my invention, it is simply necessary to have coöoperating grooves or recesses of any desired formation to receive the cement which forms the lock joint between the replaceable lenses and the vaultlight construction.

It is to be understood that the type of lens employed, as well as the type of vaultlight construction with which the lenses are used, may vary widely in practice, since my present invention is particularly directed to the novel method of and construction for forming a watertight cement lock joint between the replaceable lenses and the vaultlight construction.

It will be understood that where I refer to cement or concrete, the same is to be construed as including cementitious material, such as is adapted to be employed in vault-light construction. 115

It will now be apparent that I have devised a novel and useful construction of a vaultlight construction and method of securing lenses therein which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the

spirit or scope of the invention or sacrificing any of its advantages.

Having thus described my invention, what I claim as new and desire to secure by Letters Patent, is:—

1. The method of replacing lenses in vault-light constructions having lenses with annular ribs thereon, which consists in removing the lens to be replaced, to thereby leave an annular groove in the old concrete, coating the old concrete, surrounding the opening with cement, and filling the groove therein with cement, coating the side of a new lens having an annular groove with cement and filling the groove of the lens with cement, 30 placing a malleable coating around the upper portion of the side wall of the new lens, placing the new lens in the opening to bring its groove into register with the groove in the wall of the opening, and allowing the cement in said grooves to set to form a homogeneous mass of cement.
2. The method of replacing lenses in vault-

light constructions having lenses with annular ribs thereon, which consists in removing the lens to be replaced, to thereby leave an annular groove in the old concrete, coating 25 the old concrete, surrounding the opening with cement, and filling the groove therein with cement, coating the side of a new lens having an annular groove with cement and filling the groove of the lens with cement, 30 placing a malleable coating around the upper portion of the side wall of the new lens, placing the new lens in the opening to bring its groove into register with the groove in the wall of the opening, and allowing the cement in said grooves to set to form a 35 homogeneous mass of cement.

LOGAN WILLARD MULFORD.
